SENSITIVITY TIME CONTROL

Edward C. Kluender, Schenectady, N. Y., assignor
to General Electric Company, a corporation of
New York

Application May 3, 1946, Serial No. 666,897

3 Claims. (Cl. 179—171)

1

My invention relates to varying the sensitivity of an electron discharge device amplifier with time and more particularly to controlling the operation of a remote object detecting system in accordance with the distance to the remote objects.

In one type of remote object detecting system, recurrent pulses of radio frequency energy are transmitted in the direction of remote objects desired to be located. Reflected energy pulses from these objects are picked up by an appropriate radio receiving system and converted to a unidirectional voltage varying in accord with the intensity of the received waves. This voltage, together with time varying voltages indicating elapsed time after each transmitted pulse, is applied to a cathode ray device to produce an indication on the viewing screen thereof corresponding to the position of each remote object.

It is an object of my invention to provide improved means whereby the sensitivity of the receiving system of a remote object detecting system is varied in accordance with the time interval after the last transmitted energy pulse so that the unidirectional output voltage of the receiving system is dependent primarily on the energy reflecting properties of the corresponding reflecting object and not on the distance thereto.

It is a further object of my invention to provide improved means to control the gain of a radio receiver in a manner adaptable to use in a radio type pulse-echo object detecting system.

Another object of my invention is to provide improved means to control the sensitivity or gain of an electron discharge device amplifier after a predetermined event, which means are simple and reliable in operation, use a minimum number of circuit components, and take maximum advantage of the inherent characteristics of the amplifier circuits.

The novel features which I believe to be characteristic of my invention are set forth with particularity in the appended claims. My invention itself, both as to its organization and method of operation may best be understood by reference to the following description taken in connection with the accompanying drawings in which Fig. 1 shows a radio type pulse-echo system incorporating the apparatus of my invention and Fig. 2 illustrates the image presentation achieved by the apparatus.

Fig. 1 illustrates a radio type remote object detecting system indicative of the apparatus to which the principles of my invention may be

2

most advantageously applied. In the figure, 1 represents a pulse generator capable of generating pulses of radio frequency energy when actuated by control voltage from source 4. 5 Source 4 may, for example, produce 0.5 microsecond voltage pulses at a frequency of 1500 pulses per second across resistance 42, these pulses having the wave shape shown at 40. These pulses are applied to directional antenna 3, thereby causing a directional beam of radio frequency energy to be transmitted at the instant voltage is applied from control source 4. It is the purpose of T. R. box 2 automatically to prevent entrance of radio frequency energy to unit 5 when generator 1 is operating. This may, for example, be accomplished by providing a resonant cavity with a spark gap capable of breaking down when pulses are produced by unit 1 but to pass energy from antenna 3 to unit 5 at all other times.

Radio frequency energy from generator 1 and radiated by antenna 3 travels from the position of antenna 3 to a region containing remote objects desired to be located. These objects reflect or re-radiate the transmitted energy, thereby producing return waves travelling in the reverse direction and, after the period of time required to complete the travel, appearing again at antenna 3 from which they are applied to unit 5 by T. R. box 2. Units 5, 6, 7, and 8 constitute a radio receiver capable of producing a unidirectional voltage varying in accordance with the intensity of the reflected radio frequency energy appearing at antenna 3. This receiver may, for example, be of the superheterodyne type in which unit 5 represents the radio frequency amplifier (if any), the first detector, and a first group of intermediate frequency amplifiers (if any). Two additional stages of intermediate frequency amplification are provided by the circuits shown generally at 6, these circuits providing adjustment of the receiver gain in a manner to be described in detail hereafter. Unit 7 represents further stages of intermediate frequency amplification (if any) and the second detector whereas unit 8 represents the video amplifier portion of the receiver. The unidirectional voltage produced by video amplifier 8 is applied to the control electrode of cathode ray device 9 to vary the intensity of the ray beam of that device in accordance with the reflected radio waves appearing at antenna 3.

Source 10 is arranged to produce a saw tooth current wave after each pulse of voltage from control source 4. This unit might, for example,

include a square wave voltage generator triggered by voltage of source 4 and wave shaping amplifiers to change this voltage to the form necessary to produce a saw tooth current wave in coil 11. This current is applied to the deflecting coil of cathode ray device 9 to deflect the ray beam from the center position in accordance with the magnitude of this current, thus causing this beam to execute successive traverses from the center of the viewing screen to the periphery thereof, each swing taking place after a transmitted energy pulse. Inasmuch as the intensity of the ray beam varies in accord with the reflected energy from remote objects, and the instant of each variation occurs at a time interval after the transmitted pulse determined by the distance to the corresponding remote object, luminous spots appear on the viewing screen corresponding to the various remote objects detected, each spot appearing at a distance from the center thereof determined by the distance between the remote object and the detecting equipment and having intensity determined by the intensity of the radio echo. The axis along which the electron beam is moved by saw tooth current from source 10 is varied by means of the mechanism shown generally at 12 to correspond with the direction of most intense radiation from antenna 3. This causes the luminous spots to appear on the viewing screen in a direction from the center thereof determined by the direction of the corresponding remote objects and at a distance determined by the distances thereto, thus producing on the viewing screen a map-like indication of the location and radio reflecting characteristics of remote objects about the equipment as antenna 3 and deflecting coil 11 are rotated.

The intensity of the received radiant energy at antenna 3 varies in accordance with the distance to the remote object as well as the dimensions and construction thereof. This results from the fact that the attenuation or reduction in intensity of radio waves is determined by the distance which they travel. Hence, objects in close proximity to the detecting equipment produce stronger radio echoes and hence greater voltage at the control electrode of device 9 than the same objects if located at some distance therefrom. Consequently, the luminous indications on the viewing screen of device 9 corresponding to close objects are relatively much more intense than the indications of similar objects at some distance away. Furthermore, if remote objects are to be displayed with a high degree of brilliance it is often necessary to raise the gain of the receiving system to such a high level that extraneous echoes due to slightly reflecting objects close at hand obscure the image screen in the area corresponding to the latter objects, thereby preventing identification of larger objects located in this area. This condition is shown in Fig. 2 (a) which illustrates the appearance of the viewing screen when the gain of the system is adjusted to display remote objects while extraneous reflections from a large number of slightly reflecting objects close at hand obscure the portion of the image screen corresponding to close objects. The condition of the viewing screen with luminous points indicating only the actual relative radio reflecting properties of the remote objects is shown in Fig. 2 (b).

It is the purpose of the circuits shown generally at 6 to alter the relative sensitivity of the receiving system in such fashion as to cause remote

objects of like radio reflecting properties to produce like values of voltage at the control electrode of device 9. This is accomplished by varying the gain of these two stages of intermediate frequency amplification. The first of these stages utilizes electron discharge device 13 having its cathode connected to ground through bias resistance 14 and bypass capacitor 15 and its anode connected to unidirectional voltage source 16 by resistances 17 and 18. The screen electrode of device 13 is connected to the junction of resistances 17 and 18 and the radio frequency voltage appearing across this junction bypassed to ground by condenser 19. Voltage is applied to the control electrode of device 13 through coupling condenser 20, coil 21, and bypass capacitor 22. Coil 21 is tuned by its distributed capacitance and the interelectrode capacitances of device 13 to resonate at the frequency of the intermediate frequency amplifier, thereby causing maximum amplification of signals of this frequency which might, for example, be 30 megacycles per second. Electron discharge device 23 is connected in a manner similar to device 13, deriving its cathode bias voltage from resistance 24 and capacitor 25, its anode voltage from resistances 26 and 27 and unidirectional voltage source 28, and having its screen electrode bypassed to ground by condenser 29. Control electrode voltage is applied to this device by means of coupling condenser 30, coil 31, and bypass condenser 32, coil 31 being tuned by its distributed capacitance and the interelectrode capacitances of device 23 to resonate at the desired intermediate frequency. Amplified voltage from device 23 is applied to unit 7 through coupling capacitor 33.

The gain of the amplifier stages shown generally at 6 is determined by the unidirectional bias voltage applied to the control electrodes of devices 13 and 23 from the network comprising resistances 34, 35 and 36, potentiometer 37, and unidirectional voltage source 38. To provide maximum control in this fashion, devices 13 and 23 are of the variable-mu or remote cut-off type in which the amplification is reduced as the negative control electrode bias voltage is increased. Manual adjustment of this voltage is provided by potentiometer 37, thereby permitting the operator of the equipment to control the varying component of beam intensity of cathode ray device 9 and cause an image of maximum usefulness to appear on the image screen thereof.

In addition to the manual control of the bias voltage at devices 13 and 23 achieved through variation of potentiometer 37, automatic control of this bias is provided through the circuit including condenser 39 and source 4. It is the function of this circuit to reduce the gain of devices 13 and 23 to a varying degree after each transmitted pulse at antenna 3, the gain being reduced to a relatively great extent immediately after each transmitted pulse and to a progressively lesser extent thereafter. This variation is made to correspond approximately with the variation in the relative magnitude of the reflected waves at antenna 3 after each transmitted pulse so that the output voltage of amplifier 8 is substantially the same for all remote objects of equivalent radio reflecting properties regardless of their distance from the pulse-echo system.

The operation of the circuit of Fig. 1 to produce the varying degree of sensitivity of the amplifier shown generally at 6 may best be understood by first considering only the current path including control source 4, condenser 39,

resistance 35, condenser 32, and the current path through inductance 31, the control electrode-cathode space path of device 23, and resistance 24, the latter current path being in shunt with condenser 32. At the instant a voltage pulse appears at source 4, the charges on condensers 39, 32, and 25 remain constant and the voltage of point 41 remains at the potential associated with the bias setting of potentiometer 37. However, condensers 39 and 32 immediately begin to charge, the charge being in direction tending to make point 41 relatively more positive and taking place at a time constant determined primarily by resistance 35. The actual positive voltage at this point, however, is limited by the control electrode-cathode space path current of device 23 which begins to flow as soon as condenser 32 commences to charge. Inasmuch as this current does not charge condenser 32, it produces no voltage thereacross and correspondingly reduces the positive potential of point 41 below the potential that would exist in the absence of device 23.

Inasmuch as the charge on condenser 32 cannot change when the voltage of wave 40 disappears, the potential of point 41 remains constant at that time. However, charging of condensers 39 and 32 immediately begins, the time constant of this charge being determined principally by the value of resistance 35. Resistor 42 has a low value as compared to the resistor 35. Due to the large capacity of the capacitor 39 as compared with the capacitor 32, and the relative discharge condition of 32 resulting from its discharge by the device 23, the capacitor 39 quickly charges 32 until it has substantially the same negative potential. After their voltages become equal, they then both discharge through the resistors 36, 37 and 42. This discharge continues until capacitors 39 and 32 each reach a predetermined potential as determined by the value of resistor 37.

The above-described negative voltage at point 41 appears very soon after the pulse of wave 40 disappears since the time constant of the circuits involved is relatively short. The resultant charge on condensers 32 and 39, however, leaks off through the relatively long time constant circuit including resistance 36 and potentiometer 37. This relatively slow decay of negative voltage slowly increases the gain of amplifier 23 and thus restores the sensitivity of the receiver after the transmitted energy pulse at a rate commensurate with the decreased intensity of echo pulses at antenna 3.

During the time of each transmitted pulse, when the control electrode of device 23 is positive with respect to the cathode, amplifier 6 is inoperative. However, this does not influence performance of the pulse-echo system since breakdown of the spark gap in T. R. box 2 prevents radio energy from antenna 3 from entering the receiver during this period. Similarly, the short period of time after each pulse during which point 41 has a positive voltage does not influence system operation because T. R. box 2 does not permit radio energy to pass from antenna 3 to the receiver for a corresponding time after each pulse.

The above description has been made with reference to condenser 32 and device 23 only. The current path through resistance 34 and condenser 22, together with the current path through inductance 21 and the control electrode-cathode space path of device 13, also influences this action. In effect these current paths are in parallel with the current paths due to capacitor 32 and device

23 and, while they alter the relative distribution of voltage after the positive pulses of wave 40 and the time constant of gain restoration of the receiver, they do not alter the basic operation of the circuit.

In a particular embodiment of the above-described circuit which has been found to operate satisfactorily in practice, the following circuit conditions existed:

- 10 Wave 40—0.5 microsecond pulses of 50 volts at the rate of 1200 pulses per second.
- Capacitor 39—0.01 microfarad
- Capacitors 15, 22, 25 and 32—0.001 microfarad
- Resistances 14 and 24—120 ohms
- 15 Resistances 34 and 35—180 ohms
- Condensers 20 and 30—0.005 microfarad
- Resistance 36—3000 ohms
- Source 38—210 volts
- Potentiometer 37—210,000 ohms
- 20 Devices 13 and 23—Type 6AK5

It has heretofore been considered necessary in gain control devices of the type herein described to apply a negative voltage pulse to the control electrodes of the electron discharge devices desired to be rendered insensitive. This has required the use of special equipment to generate these pulses in a satisfactory manner, such equipment generally requiring multivibrators, gas tubes, rectifiers, amplifiers, additional transformers and the like. This not only increases the expense of the equipment but also decreases the reliability and adds to the complexity thereof. I have discovered that a method contrary to that of the prior art produces superior and unanticipated results, probably as a result of the theory outlined herein. Thus by taking advantage of the inherent characteristics of the circuits, I am enabled to produce a negative bias voltage varying in accordance with the desired gain control without the disadvantages of the prior art circuits.

While I have shown and described a particular embodiment of my invention, it will be obvious to those skilled in the art that changes and modifications may be made without departing from my invention in its broader aspects. In particular, this system is applicable to radio receivers and electron discharge device amplifiers other than the pulse-echo equipment specifically described herein. Furthermore, the principles of this invention may be applied to pulse-echo equipments utilizing waves other than radio waves and displaying the location of remote objects in a manner different from that described herein. I therefore aim in the appended claims to cover all such changes and modifications as fall within the true spirit and scope of my invention.

What I claim as new and desire to secure by Letters Patent of the United States is:

- 60 1. In a radio detecting apparatus of the type wherein radio energy pulses are successively transmitted and the corresponding reflected energy received to determine the location of remote objects, an electron discharge device having a cathode, control electrode, and anode, said device being capable of reducing the sensitivity of said system as said control electrode has increased negative potential relative to said cathode, pulse generating means to produce a voltage wave having positive pulses at the instants of said transmitted pulses, means to impress said positive pulses upon a time constant network comprising first and second capacitors in series, means connecting the control electrode-to-cathode path 65 of said device across said second capacitor, said
- 70
- 75

path being rendered conductive by said pulse to provide a low impedance across said second capacitor during each pulse, said network having a low time constant relative to the pulse period, said first capacitor being charged rapidly by said pulses and discharging rapidly into said second capacitor at the termination of each pulse, thereby to reduce the sensitivity of said system, and means for discharging said capacitors at a predetermined rate to restore said sensitivity.

2. In combination, an electron-discharge device having cathode, anode, and control electrodes, a pulse generating source, two capacitors in series connection across said source, means connecting the cathode-control electrode space path of said device across one of said capacitors so that said control electrode becomes positive with respect to said cathode when a positive pulse is applied from said source, means for applying a negative potential to said control electrode at the termination of said pulse, thus causing said control electrode to have a negative potential relative to said cathode, and means for discharging said capacitors to remove said negative potential at a predetermined rate.

3. A sensitivity control circuit comprising, in combination, an amplifier including an electron-discharge device having amplification determined

by the voltage between a control electrode and a cathode, a source of positive voltage pulses, means to impress said pulses upon a time constant network comprising first and second capacitors in series, means connecting the control grid-to-cathode space path of said device across said second capacitor, said path being rendered conductive by said pulses to shunt said second capacitor for the duration of said pulses, said network having a short time constant relative to the pulse period, said first capacitor being charged for duration of said pulses and charging said second capacitor rapidly upon termination of each pulse, thereby to reduce the amplification of said device, and means for discharging said capacitors to restore the amplification of said device at a predetermined rate.
